United States Patent Office.

ORRIN C. DOW AND ALFORD C. HARVEY, OF ST. JOHNSBURY, VERMONT.

Design No. 4,748, dated April 4, 1871.

DESIGN FOR A TELEGRAPHER'S BADGE-PIN.

The Schedule referred to in these Letters Patent and making part of the same.

To all whom it may concern:

Be it known that we, ORRIN C. Dow and ALFORD C. HARVEY, of St. Johnsbury, in the county of Caledonia and State of Vermont, have invented certain Improvements in Designs for Badge-Pins, of which the following is a specification, reference being had to the accompanying drawing.

Our invention consists in the production of a novel design for a badge-pin, more especially intended for the use of telegraph operators.

This design is clearly shown and illustrated in the accompanying photograph. This form, shape, or

configuration is impressed or given to any suitable metal for the production of a badge-pin.

Having thus described our invention,
What we claim is—

The design for a badge-pin, substantially as herein shown and illustrated.

ORRIN C. DOW.
ALFORD C. HARVEY.
